UNITED STATES PATENT OFFICE.

EDWARD LEVI, OF ZURICH, SWITZERLAND.

MOLDING-BOX FOR THE MANUFACTURE OF BUILDING-STONES.

SPECIFICATION forming part of Letters Patent No. 709,495, dated September 23, 1902.

Application filed June 27, 1902. Serial No. 113,474. (No model.)

To all whom it may concern:

Be it known that I, EDWARD LEVI, a subject of the King of Würtemberg, residing at Zurich, Switzerland, have invented new and useful Improvements in Molding-Boxes for the Manufacture of Building-Stones, of which the following is a specification.

The novelty of the present invention consists of an improvement in a molding-box for the production of stones for building, the same possessing a bottom with a front and back wall attached thereto by joints, also removable side walls and intermediate partitions parallel to the latter, which divide the space formed by the four exterior walls into regular rectangular chambers, the side walls having movable bows or straps reversible upward, with stretching-screws for the purpose of pressing the front and back wall against the side and partition walls, the bottom of the molding-box having rectangular hollowed channels in every separate chamber and above the chambers and projecting into them removable cross-bars, which rest in slits in the front and back walls, and having in every chamber on the inner side of the front wall projections tapering off downward and on the inner side of the back wall similarly-formed hollowings for the purpose of producing stones of a rectangular form, having at the lower side rectangular noses and at their upper side corresponding grooves and having also at one end hollowings tapering downward and at the other end similarly-shaped projections.

The object of the invention is represented in the accompanying drawings in a simple form.

Figure 1 shows a partial front view and longitudinal section of the molding-box along the line A B in Fig. 2; Fig. 2, a view of the same from above; Fig. 3, a cross-section along the line C D in Fig. 2; Fig. 4, a perspective view of a building-stone produced by means of the molding-box.

The molding-box consists, essentially, of the bottom 1, the movable front and back walls 2 and 3, and the two removable side walls 4 and 5. The bottom 1 has on its upper side at regular distances rectangular hollowed channels 6, the sides of which taper conically away downward, and has at its two

side ends rabbets or additional pieces 7 for the walls 4 and 5. At its under side cross-pieces 8 are attached, having jointed ends, which are connected on both sides by pins 9. 55 The front and back walls 2 and 3, with their flaps 10, rest on these pins 9, on which they turn outward. The two walls 2 and 3 have vertical guides 11, into which the side walls 4 and 5, which can be lifted in and out, are fitted. 60 On the upper part and outer side of the same two bows 13 are adjusted, movable around screws 12 and provided with noses which catch into the detent-pins 14 and which have at the top stretching-screws 15. These stretching-screws act on the upper corners of the front and back walls—that is to say, they press the walls 2 and 3 firmly against the intermediate walls 4 and 5. The front wall 2 is provided on its inner side with projections 70 16, tapering downward, while the back wall 3 has on its inner side as many correspondingly-shaped hollowings 17, these projections and hollowings being exactly opposite to each other and in the axis of the hollowed channels 6. Immediately between each pair of projections 16 and hollowings 17—that is to say, between two hollowed channels 6—partition-walls 18, removably adjusted in vertical guides, fit into the front and back walls, 80 which partition-walls divide the box formed by the walls 2 and 3 and 4 and 5 into several regular rectangular smaller spaces or chambers. In the middle of the upper open part of these chambers and inserted in the walls 85 2 and 3 in corresponding slits 19 cross-bars 20 are placed, which taper downward and project into the chambers and the upper sides of which are even with the upper edges of all the box-walls. Below these cross-bars and 90 about half-way up the height of the chambers there are longitudinal apertures 21 in the front and back walls, tapering slightly conically from top to bottom, into which are inserted wedge-shaped rods 22, running right 95 through the box from one side to the other.

The necessary material in a fluid form for the molding of the stones is poured into each separate chamber from the upper open side. After loosening the stretching-screws 15, reversing the bows 13, removing the cross-bars 20, and withdrawing the wedge-shaped rods

22 the walls 2 and 3 can be turned back side-
wise, as indicated in Fig. 3 by the dotted lines.
In the same manner the two side walls 4 and
5 and the intermediate partitions 18 are re-
5 moved and we have a number of stones ready
molded corresponding to the number of cham-
bers. Their shape is that shown in Fig. 4—
i. e., rectangular and corresponding to the di-
mensions of the chambers—having at their
10 lower sides noses, tapering downward, corre-
sponding to the hollowed channels 6 of the
bottom of the box 1, and on their upper sides
being provided with grooves, narrowing down-
ward, corresponding to the shape of the cross-
15 bars 20. On two of the side surfaces are con-
ically-tapering hollows formed by the same-
shaped projections 16 of the front wall 2, and
on the other side surfaces are projections, ta-
pering down conically, corresponding to simi-
20 lar hollowings 17 in the back wall 3 of the box,
while an aperture situated in the middle of
the stone and running through all its length
corresponds to the cross-section of the wedge-
rod 22. The length of the molding-box or the
25 number of chambers can of course be larger
or smaller, and the other dimensions can also
be larger or smaller.

Having now particularly described and as-
certained the nature of my said invention and
30 in what manner the same is to be performed,
I declare that what I claim is—

1. A molding-box for the manufacture of
building-stones consisting of a bottom and
front and back walls attached thereto by
35 joints, of removable side walls and interme-
diate partition-walls parallel to the same, run-
ning from the front to the back wall, dividing
the space formed by the four walls into regu-
40 lar rectangular chambers, and of means to
press the front and back walls against the
side walls and partitions, the bottom of the
box having rectangular hollowed channels in
45 each separate chamber and above the cham-
bers and projecting into them cross-bars which
are removably adjusted in slits in the front
and back walls and having in each chamber
50 on the inner side of the front wall projections
tapering downward and on the inner side of
the back wall similarly-shaped hollowings for
the purpose of producing stones of a rectan-
55 gular form, having at their lower side rectan-
gular noses and at their upper side corre-
sponding slits and on the one end hollowings

tapering away downward and on the other
end similarly-formed projections.

2. In a molding-box for the manufacture of
building-stones consisting of a bottom and
front and back walls attached thereto by
joints, of removable side walls and interme-
diate partition-walls parallel to the same, 60
means for pressing the front and back walls
of the box against the side and intermediate
walls, consisting of bows reversible upward,
movably attached to the side walls, which
bows have stretching-screws acting on the 65
front and back walls and means to retain the
bows in their lower position.

3. In a molding-box for the manufacture of
building-stones consisting of a bottom and
front and back walls attached thereto by
joints, of removable side walls and interme-
diate partition-walls parallel to the same, 70
bows reversible upward, movably adjusted to
the side walls which bows are provided with
stretching-screws for the purpose of pressing 75
the front and back walls against the side and
intermediate walls and means to retain the
bows in their lower position consisting in the
fact that the bows have noses catching into
pins which are fixed to the side walls of the 80
box.

4. In a molding-box for the manufacture of
building-stones consisting of a bottom and
front and back walls attached thereto by
joints, and of removable side walls, partition-
85 walls parallel to the side walls dividing the
space formed by the four exterior walls into
regular, rectangular chambers, each separate
chamber having in its bottom hollowed chan-
nels and, at the top, cross-bars, and having 90
also on the front wall inner projections taper-
ing conically downward and on the back wall
similarly-formed inner hollowings, and aper-
tures in the front and back walls arranged
95 longitudinally in every chamber in which rods
of corresponding shape are inserted for the
purpose of forming apertures running longi-
tudinally right through the stone.

In testimony whereof I have signed my
name to this specification in the presence of 100
two subscribing witnesses.

EDWARD LEVI.
